UNITED STATES PATENT OFFICE.

MARCUS T. LOTHROP, OF CANTON, OHIO, ASSIGNOR TO THE TIMKEN ROLLER BEARING COMPANY, OF CANTON, OHIO, A CORPORATION OF OHIO.

PROCESS OF MAKING CAGES FOR ROLLER BEARINGS.

Application filed November 12, 1926. Serial No. 147,939.

My invention relates to a process of making cages for roller bearings.

A roller bearing cage is usually made of a single piece of thin metal of cylindrical or conical form with pockets therein for the rollers. Heretofore it has been the practice to make such pockets by punching a hole of slightly greater length than the roller and striking up the sides thereof into the form of wings of suitable width and curvature to conform to the surface of the roller. Heretofore it has been the practice to punch the pocket hole in the form of the capital letter I, that is, the punch hole is widened laterally at its ends to provide for the subsequent operation of pressing up the wings. The result of such practice is to make the wings shorter than the pocket hole and shorter than the roller therein; and in the case of cages made of heavy metal, such shortening of the wings amounts to about one-quarter of the entire length of the pocket. The purpose of the present invention is to devise a process which will make the wings of the cage the full length of the pockets or of the rollers therein. Accordingly the invention consists in the process hereinafter described and claimed.

In the accompanying drawing, wherein like reference numerals refer to like parts wherever they occur,

Fig. 1 is a side view of a conical blank suitable for making a cage for conical roller bearings, a portion of the right side being shown in section.

Fig. 2 is a view of a portion of said blank with a quadrangular pocket hole punched therein,

Fig. 3 is a view of said portion of the blank with both the quadrangular pocket hole and smaller holes at the respective corners thereof,

Fig. 4 is a view of said portion with the metal between the pockets and the respective corners of the quadrangular hole severed and the wings struck up,

Fig. 5 is a sectional view on the line 5-5 of Fig. 4,

Fig. 6 is a cross-section on the line 6-6 of Fig. 4,

Fig. 7 is a side view of the finished cage; and

Fig. 8 is a detail view of a portion of a blank punched in accordance with the usual practice heretofore prevailing.

The cage illustrated in the accompanying drawing is designed for use with conical or taper rollers. It comprises a conical shell A, preferably made in a single piece with a continuous series of pockets B for the rollers. Such shells have been made out of sheet metal and also out of tubing.

Heretofore, it has been the practice to punch each pocket with a punch (or punches) of the form of the capital letter I, which produces a punch hole 1^a of the same form, as shown in Fig. 8. According to the present process, the ends of the main punch are straight and parallel, as heretofore, but the sides extend in straight lines 70 from one of such ends to the other so that the hole 1 punched in the blank C by my punch is of quadrangular form. The sides of such hole 1 are parallel for cylindrical rollers or converge somewhat for taper 75 rollers.

Small holes 2, preferably circular, are then punched or drilled through the wall of the cage a slight distance away from the corners of the quadrangular hole 1 made by the main punch, and with the centers of said small holes substantially in line with the ends of the main hole. This places the small holes 2 in proper position with reference to the lines on which the wings C are to be struck up, and it also places such small holes with only a small amount of metal intervening between them and the main punch hole, such intervening metal being thinnest in the line of the end walls of said main hole.

When the cage blank has been provided with the main punch holes 1 and the corner holes 2 therefor, it is submitted to the operation of striking up the wings C, which operation is performed in an ordinary press with forming dies that extend the full length of the wings C. This operation shears the thin walls of metal that separate the small corner holes 2 from the main punch hole 1, such shearing being in line with the ends of the main punch hole and thereby making the wings C the full length of such hole.

The wings of the cage extend the full length of the pockets and, being conformed to the rollers, are effective throughout the 105 entire length of the rollers for the purpose of guiding, spacing and positioning the same. The extra length of the wings of my cage in comparison with previous cages is of great advantage in various ways. For in-

stance, the endmost portions of the rollers are most sensitive to the guiding action of the wings, and my wings are enabled to co-operate with the rollers closer to their ends than has heretofore been practicable. Again, by reason of their greater length, my wings distribute the wear of both the wings and the rollers to better advantage than previous constructions; and also by reason 10 of the extra length of my wings, they are stronger and more rigid than shorter wings. Another great advantage is that a quadrangular punch is very strong and durable and easy to make whereas the I-shaped 15 punches heretofore used are more expensive and shortlived and liable to break. This last mentioned advantage is of the greatest importance with cages of thick metal, such, for instance, as number sixteen gage.

20 While the preceding description assumes that the process begins with a tubular or cylindrical blank, it is obviously applicable to processes that start with a flat blank. Likewise, while the preceding description assumes that the main hole is punched before 25 the formation of the small corner holes, such sequence of operation might be reversed or both the main hole and the corner holes might be formed simultaneously.

30 What I claim is:

1. The process of making roller bearing cages, which consists in providing the blank with holes for the pockets and with smaller holes near the corners of said pocket holes

and striking up wings along lines that extend alongside said pocket holes and through said small holes. 35

2. The process of making roller bearing cages, which consists in providing the blank with holes for the pocket and with smaller 40 holes near the corners of said pocket holes and striking up wings along lines that extend alongside said pocket holes and through said small holes thereby shearing the metal intervening between the pocket holes and the 45 small holes.

3. The process of making roller bearing cages, which consists in providing the blank with quadrangular holes for the pockets and with smaller holes adjacent thereto and in alignment with the ends of said pocket holes, and striking up wings alongside of said pocket holes and simultaneously shearing the metal between the corners of the pockets and 50 said small holes. 55

4. The process of making roller bearing cages, which consists in punching quadrangular holes in the blank, then punching small holes in alignment with the ends of 60 said quadrangular blanks and at a slight distance from the corners thereof, and then striking up wings alongside of the quadrangular holes along lines that pass through the smaller holes and thereby shearing the 65 intervening metal.

Signed at Canton, Ohio, this 8th day of November, 1926.

MARCUS T. LOTHROP.
